UNITED STATES PATENT OFFICE.

JOSEPH STONE, OF LAWRENCE, MASSACHUSETTS.

MACHINE FOR SPOOLING YARN FROM THE CHAIN.

SPECIFICATION forming part of Letters Patent No. 365,949, dated July 5, 1887.

Application filed June 8, 1885. Serial No. 163,011. (No model.)

To all whom it may concern:

Be it known that I, JOSEPH STONE, of Lawrence, County of Essex, and State of Massachusetts, have invented an Improvement in Machines for Spooling Yarn from the Chain, of which the following description, in connection with the accompanying drawings, is a specification, like letters on the drawings representing like parts.

10 The object of this invention is to facilitate the operation of spooling in separating and rewinding yarn which has been wound in the chain on a beam, and to economize time in such operation.

15 In methods now generally practiced for winding dyed yarns upon bobbins to be used in loom-shuttles, a large number of ends—several hundred—are wound upon one beam in a beam-ing-machine, and the ends are led to the bob-bins or spindles of several spooling-machines; but such plan, besides requiring several spooling-machines to thereby enable all the yarns to be taken simultaneously from the single beam, also results in great waste of time, for 25 in case any one yarn or end breaks, the spindles in all the machines have to be stopped, and all remain at rest until the end has been pieced or mended.

It has been proposed to wind printed warp-30 threads upon a beam or large bobbin having flanges which divide it in the direction of its length into a series of compartments, each of the latter to receive a certain number of ends or threads of the warp, and to rewind from 35 the said compartments successively onto a series of smaller bobbins resting upon rollers and driven thereby, the number of threads wound in each compartment corresponding with the number of receiving-bobbins in the 40 winding-machine. In accordance with my invention, I provide a beam similar to that just described, having a series of flanges or division-plates at a short distance apart, usually about four inches, thus separating the beam 45 into several sections which are all filled simultaneously, or at one winding operation, by ends or yarns taken from a chain, each section of the beam between the flanges or division-plates containing, for instance, one hundred 50 ends or yarns, or as many of the latter as the spooling-machine, in connection with which

the beam is to be used in rewinding and separating, has spindles. This beam, for convenience of transport, I mount on a truck, which may be moved into position adjacent to the 55 winding-machine. In the operation of re-winding, the yarns or ends on a single section of the beam are led separately to the spindles of a spooling-machine, so that the sections are 60 unwound independently of each other, thus leaving undisturbed the sections not at such time being unwound.

Figure 1 is a plan view of an apparatus by which my invention may be carried into effect; Fig. 2, an end view of Fig. 1, that part thereof 65 beyond the dotted line *x x* being omitted.

The beam is provided with usual heads, *a*, and with a series of independent heads or division-plates, *a²* *a³*, thus constituting several yarn-receiving sections *b b*, to receive the yarn 70 or ends *c*, each section *b* being of sufficient size to receive as many yarns or ends as there are spools *d* and spindles *e* in the spooling-machine D.

In using my apparatus the dyed yarns, pref-75 erably taken from a chain, are simultaneously wound upon several independent or separate sections of the beam between the flanges *a²* *a³*, the yarn being at the same time brushed in usual manner, the expense of simultaneously 80 winding all the sections being substantially the same as though but one section were wound, the time being the same. Having wound the beam so that all its sections contain ends or 85 yarns, the said beam will be mounted in suitable bearings, C, herein shown by dotted lines, (see Fig. 2,) extended from an upright, C', of a truck, C², provided with rollers C² to roll upon the floor, the said truck having a locking pin or device, 2, to engage holes 3 in a cleat 90 screwed to the floor, the pin in the cleat locking the truck in place while the yarns or 95 ends of any one section are being taken off by the spindles and wound upon spools or bobbins carried by the said spindles, the said 100 yarns or ends in their passage from the beam being, as herein shown, passed over rolls *d¹*, and thence over guiding sheaves or spools *d²* on studs *d³*, the yarn being thereafter separated by the pins of one or more raddles, *f f'*, and thence through guides *g* of a traverse bar, *h*.

In the drawings, Fig. 1, the beam is shown as

having had the yarns or ends unwound from six sections thereof, the seventh section being in the process of being taken off, the five remaining sections being shown as containing yarn.

5 By winding the yarns upon the beam in sections between the series of flanges, each section b of the said beam containing only the number of yarns which can be wound by a single spooling-machine, it is possible to employ any usual 10 spooling-machine and wind the yarn from the beam economically and practically, the breaking of a yarn or end in no case stopping more than the spindles of the one machine. A beam, such as described, for receiving the dyed yarns 15 to be wound therefrom upon spools carried by the spindles, the yarn being so applied that there may be unwound from it only the number of ends corresponding with the spindles of one spooling-machine, results in great economy and may be employed to advantage in mills where it would be inexpedient to have several spooling-machines in operation at one time; and, further, by a beam such as described the yarns may be of different colors 20 upon different sections. With a beam having several intermediate flanges, leaving separate sections to contain just enough yarn to co-operate with the spindles and spools or bobbins of one machine, weft-yarn in quantity to fill 25

all or but part of the sections may be wound 30 upon the beam; but being wound in sections or divisions, as stated, just enough yarn in each division to supply one spooling-machine, the said weft yarn may be removed from the beam from time to time as actually needed, 35 and not all at one operation, as heretofore usually practiced; and by limiting the quantity of yarn, as stated, an end section of weft-yarn may be economically and practically stored for use as desired. 40

I claim—

The combination, with the spindles of a spooling or twisting machine, of a yarn-beam having several flanges by which it is divided into sections, to contain yarns equaling in 45 number the said spindles, a movable truck adapted to support the said yarn-beam, guide-rolls, guiding sheaves or spools, raddles, and traverse-bars having guides, to operate substantially as set forth. 50

In testimony whereof I have signed my name to this specification in the presence of two subscribing witnesses.

JOSEPH STONE.
